UNITED STATES PATENT OFFICE.

WILLIAM WELSH, OF KINCARDINE, ONTARIO, CANADA.

AEROPLANE.

Application filed December 11, 1920. Serial No. 429,938.

To all whom it may concern:

Be it known that I, WILLIAM WELSH, of the town of Kincardine, in the county of Bruce, in the Province of Ontario, Canada, 5 have invented certain new and useful Improvements in Aeroplanes, of which the following is the specification.

My invention relates to improvements in aeroplanes and the object of the invention 10 is to devise an aeroplane which, while retaining the advantages of the ordinary or horizontal flight machine will at the same time be capable of direct lift in taking off or in landing. A further object is to provide means for varying the centre of gravity 15 of the machine whereby the inclination of the planes may be varied or wherein the machine may be turned so as to constitute a direct lift machine. A still further object is to provide means whereby the stopping of one engine of the machine will not stop the propellers and thus render a propelling mechanism inoperative through the stopping of one engine.

20 My invention consists of the parts constructed and arranged all as hereinafter more particularly described and illustrated in the accompanying drawing in which:

Fig. 1 represents a front view of an aeroplane constructed according to my invention.

Fig. 2 is a rear view.

Fig. 3 is a plan view.

Fig. 4 is an enlarged vertical section 35 through the line 4—4 Fig. 1, and

Fig. 5 is a vertical section through the line 5—5 Fig. 1.

Like characters of reference indicate corresponding parts in the different views.

40 1 is the lower plane and 2 the upper plane suitably mounted on the lower plane by the struts 3 and the cross stays 4. The wing tips 5 of the upper plane are inclined downwardly, such wing tips being supported 45 by the diagonal struts 6. 7 is an elevator provided at the front of the upper plane and suitably hinged thereto. 8 are the propeller shafts extending longitudinally of the machine, each shaft 8 being provided with the forward and rear propellers 9 and 10 respectively.

50 11 are engines suitably mounted on the machine and provided with clutches 12, carrying the sprocket wheels 13 adapted to drive the sprocket wheels 14 on the respective shafts by the chains 15. 16 are sprock-

ets in the vicinity of the forward ends of the shafts 8 connected by the cross chain 17 for connecting the two shafts together, it being understood that the shafts are mounted between the planes 1 and 2 in any suitable manner such as by bearing brackets 18 on the struts 3. 19 is the nacelle of the machine.

20 are rudders suitably mounted in the vicinity of the ends of the lower plane. 21 is a depending bracket secured to the underneath side of the lower plane 1 and having the straight rod 22 pivotally connected thereto. 24 is a cable secured at one end 25 to the free end of the rod 22 and extending over the sheaves or blocks 25 mounted on the upper plane, the other end of the cable being wound on the drum 26 detachably mounted on one of the shafts 8 by the clutch 27.

28 is a ball shaped weight slidably mounted on the rod 23. 29 is a cable connected at one end to the weight 28 and extending up through the sheave 30 and wound upon the drum 31 detachably secured to the other shaft 8 by the clutch 32. 33 are U-shaped brackets extending rearwardly from the upper and lower planes and adapted to enclose the rear propellers 10.

85 The operation of the machine is as follows:

Preparatory to taking off, the machine will be in the direct lift position and will rest on ground on the brackets 33, the rod 22 being drawn up by means of the cable 24 and the weight 28 being drawn up by means of the cable 29.

On starting the engines and the clutches 12 being thrown in the propellers will be 95 revolved and will act as helicopters, thus lifting the machine off the ground the desired distance. By dropping the rod 22 and allowing the weight 28 to slide down thereon, the centre of gravity of the machine will be altered and the machine will 100 be turned into the substantially horizontal flying position, the propellers now propelling the machine.

If it is desired to climb, in addition to 105 using the elevator 7 the rod 22 can be drawn up a certain extent by means of the cable 24, which will throw the weight 28 rearwardly, thus altering the centre of gravity of the machine and swinging it into 110 the climbing position.

When desiring to land, the rod 22 is

- pulled up a further extent which will cause the weight to be displaced further in a rearward direction, thus causing the machine to turn into the vertical or direct lift position. Now, by slowing down the engines the lift of the propellers will be lessened and the machine will come to the ground, the rod 22 and the weight 28 being drawn up in order to prevent them striking the ground when landing. It is intended that the machine shall land on the brackets 33, which take the place of the ordinary landing or chassis carriage.
- 15 It will be seen that by interconnecting the propeller shafts 8, should one engine stop, the other engine will drive the two shafts and thus do away with the necessity of having to shut down the other engine, 20 and plane to the ground.

25 Steering in a horizontal plane is effected by putting over the rudder on the side of the machine to which it is desired to turn. Thus should it be desired to turn to the left, 30 the left hand rudder 20 is put over, which acts as a drag on the left hand side of the machine, and thus the machine will turn to the left.

What I claim as my invention is:

- 30 1. In an aeroplane, the combination with the main planes, of a rod pivotally connected underneath the same, a weight slidably mounted on the said rod, means for swinging up the rod and means for drawing up the weight on the rod independently of the means for swinging up the rod.
2. In an aeroplane, the combination with the main planes and propellers rotatably mounted in front of and behind such main 40 planes, of a rod pivotally connected at its upper end to the machine, a weight slidably mounted on the said rod, means for drawing the rod up and means for drawing the weight up independently of the rod.

3. In an aeroplane, the combination with the main planes, and propellers rotatably mounted in front of and behind such main planes, of a straight rod having a bent upper end pivotally connected at its upper end to the machine, a weight slidably mounted on the said rod, a cable connected to the free end of the rod, said cable extending up into the machine, means for winding up said cable, a cable secured to the weight, said second cable extending up into the machine and means for winding up the second cable.

4. In an aeroplane, the combination with the main planes, and propellers rotatably mounted in front of and behind such main planes, of brackets extending about the rear propellers, means for turning the machine into the vertical or direct lift position for landing or taking off, said machine landing and taking off on said brackets. 65

5. In an aeroplane, the combination with the main planes, of longitudinal propeller shafts rotatably mounted between the said planes, propellers on the forward and rear ends thereof, independent engines driving the respective propeller shafts, sprocket wheels on the shafts, a cross chain extending over said sprocket wheels for connecting the two shafts together, a straight rod having a bent upper end pivotally connected 75 below the lower plane, a weight slidably mounted thereon, drums on the respective propeller shafts, clutches detachably securing the drums to such shafts, a cable connected at one end to the free end of the rod, the other end wound upon one of the drums, a second cable connected at one end to the weight on the rod and the other end wound around the other drum. 80
